UNITED STATES PATENT OFFICE.

EDMUND S. POMYKALA, OF SAVANNAH, GEORGIA.

PILING.

Application filed July 5, 1927. Serial No. 203,666.

This invention relates to a means for excavating in wet and infirm earth, sand, etc. and has for one of its objects the conversion of such earth to a solid firm condition by 5 means of direct refrigeration so that it may better be worked with. Another object is the provision of suitable metal piling for the application of the freezing medium.

Referring now to the drawings,

10 Figure 1 shows a side elevation of one form of metal pile for carrying out the invention, the form shown being a combination pipe pile and sheet pile.

Figure 2 shows a second form of combination sheet and pipe pile in side elevation.

Figure 3 is a side elevation, partly in section, of a pipe pile, showing the connections for the entrance and exit of the refrigerating agent.

20 Figure 4 is a plan view of the pile shown in Figure 1.

Figure 5 is a plan view in section of the pile shown in Figure 1, said view being taken on the line 5—5 of Figure 1.

25 Figure 6 is a plan view of the pile shown in Figure 2.

Figure 7 is a plan view in section of the pile shown in Figure 2 taken on the line 7—7 of that figure.

30 Figure 8 is a diagram showing the arrangement of piling, refrigerating machinery and connections therefor on a plot of ground to be excavated. The diagram corresponds to a plan view.

35 Referring now again to Figures 1 to 7, inclusive, numeral 1 indicates a pipe or shell, closed as to its bottom portion 2, the walls here being materially thickened to withstand driving. The upper end of the shell is 40 threaded as shown at 3, the threads serving for the attachment of a cap 4. Into the said cap, an inlet pipe 5 extends, the said pipe being intended for the entrance of a refrigerant, preferably ammonia, either in gaseous or liquid anhydrous forms.

45 It will be noticed from Figure 3 that the pipe 5 extends almost to the bottom of the shell, thus insuring a liquid seal on the pipe if liquid anhydrous ammonia is used. Into one side of the cap 4, a second pipe 6 is 50 threaded, this pipe being the exit for the expanded refrigerant.

55 It will be evident from the above disclosure that if the pile be driven into soft, wet earth or sand and a refrigerant introduced into the pipe 5, the natural expansion of such

substance within the shell will produce intense cold which will readily exert its effect through the walls of the shell to freeze the surrounding earth.

To avoid the damage due to the cap 4 and its connecting pipe which would inevitably occur if it were attempted to drive a pile of this nature with such a cap on it, the cap 4 may be replaced with a plain cap having no piping connections and having heavier walls than the usual cap. After the pile is fully driven, replacement of the plain heavy cap by the cap 4 may be readily accomplished.

The advantages of refrigerating piling and sheet steel piling may be combined into one structure, of which combined construction Figures 1, 2, 4, 5, 6 and 7 are examples.

In the construction shown in Figure 1 in side elevation and in Figures 4 and 5 in plan, a pile of the kind shown in Figure 3 is shown at 1 in the middle part of the web portion 7 of a sheet steel pile 8. It will be noticed from Figures 4 and 5 that the pipe pile lies equally on either side of the web 7. Such a construction may be made by welding halves of a split sheet steel pile to the pipe pile.

In this construction the pipe pile extends completely to the bottom of the sheet steel pile but not as far as the top of the latter. 85 By such a construction, the combination pile may be driven by blows on the top of the sheet steel pile without damaging the top of the pipe pile. An opening 9 is provided in the sheet steel pile around the head of the 90 pipe pile so as to allow free access to the head of the said pipe pile.

It will be noticed from Figures 4 and 5 that the sheet steel pile is provided with the usual locking joints 9 and 10 on its edges. 95

In the form illustrated in Figures 2, 6 and 7, protection of the head of the pipe pile is provided by sheet steel head 11. The lower part of the pipe pile is however left free of any encumbrances so that it may enter the 100 ground easily.

The form of sheet steel head here employed dispenses with the usual locking joints on the edges of the pile shown in Figures 1, 4 and 5 and instead uses a special edge shown at 12 in Figures 2, 6 and 7. Such edge is made of a pair of angle irons 12 riveted to the flat web 13 in the position shown. An opening 9 around the head of the pipe pile is also provided.

110 In Figure 8 a complete refrigerating plant is shown connected to a series of piles in

place in the ground, all of the piping connections being shown. Since the units of the refrigerating plant bear legends in the drawing they are not designated by numerals. The flow of refrigerant through them is indicated by arrows.

Liquid anhydrous ammonia is allowed to expand through a reducing valve 14 into a line of pipe in which the piles 1 are connected in series. In practice as many rows of piles are successively driven into the ground and operated according to the area and condition of the zone to be treated.

The arrangement of piling and exterior piping is well within the skill of the engineer to work out for himself and may be varied to suit various conditions without departing from the spirit of the invention.

Having now described the invention, I claim—

1. A hollow pile adapted to contain a liquid and allow its free passage therethrough, said pile having a tubular middle portion and a pair of metal wings or webs extending horizontally therefrom.

2. A hollow pile adapted to contain a liquid and allow its free passage therethrough, said pile having a tubular middle portion and a pair of metal wings or webs extending horizontally therefrom, said webs bearing locking joints on their outside vertical edges.

3. A hollow pile adapted to contain a liquid and allow its free passage therethrough, said pile having a tubular middle portion and a pair of metal wings or webs extending horizontally therefrom, said webs bearing locking joints on their outside vertical edges,

the said webs being joined together above the top of the hollow pile.

4. A hollow pile adapted to contain a liquid and allow its free passage therethrough, said pile having a tubular middle portion and a pair of metal wings or webs extending horizontally therefrom, said webs bearing locking joints on their outside vertical edges, the said webs being joined together above the top of the hollow pile, and being provided with an opening in the web immediately around the top of the hollow pile.

5. A combination tubular pile and sheet pile comprising a middle portion of tubular section adapted for the passage of a liquid or gas therethrough and a plurality of sidewardly extending webs welded to the tubular section.

6. As an article of manufacture, a hollow pile through which a refrigerant is circulated to freeze earth in which the pile is embedded, and a plurality of wings radiating from the pile.

7. As an article of manufacture, a hollow pile through which a refrigerant is circulated to freeze earth in which the pile is embedded, a plurality of wings radiating from the pile, and means for connecting the edges of the wings of adjacent piles.

8. As an article of manufacture, a hollow pile through which a refrigerant is circulated to freeze earth in which the pile is embedded, oppositely extending wings on the pile, and coupling means on each of the wings for engagement with the wings of an adjacent identical pile.

EDMUND S. POMYKALA.
